HOUSING FOR MULTIPLE LENS GRINDING AND POLISHING UNITS

Thomas A. Walsh, Fountain Valley, Calif., assignor to
R. Howard Strasbaugh, Inc., Los Angeles, Calif.

Filed June 22, 1972, Ser. No. 265,208

Term of patent 14 years

Int. Cl. D15—09; D16—99
U.S. Cl. D37—1 A

FIG. 1 is a front elevational view of a housing for multiple grinding and polishing units, showing my new design.

FIG. 2 is an end elevational view as seen from the right of FIG. 1.

FIG. 3 is a top plan view of the same.

FIG. 4 is an end elevational view as seen from the left of FIG. 1.

FIG. 5 is a rear elevational view thereof.

I claim:

The ornamental design for a housing for multiple lens grinding and polishing units, substantially as shown.
